[57] CLAIM

The ornamental design for a hand held optical scanner front face portion, as shown and described.

DESCRIPTION

FIG. 1 is a front perspective view of a hand held optical scanner front face portion showing our new design;

FIG. 2 is a top front perspective view thereof;

FIG. 3 is a bottom front perspective view thereof;

FIG. 4 is a right side elevation perspective view therof; and,

FIG. 5 is a left side elevation view thereof.

The broken line drawing in all figure views is for illustrative purposes only and forms no part of the claimed design.
